(57) CLAIM

The ornamental design for a camcorder case, as shown and described.

DESCRIPTION

FIG. 1 a front elevational view of a camcorder case embodying our new design;

FIG. 2 is a front elevational view thereof;

FIG. 3 is a rear elevational view thereof;

FIG. 4 is a left side elevational view thereof;

FIG. 5 is a top plan view thereof; and,

FIG. 6 is a perspective view thereof, showing the inclusion of an optional shoulder strap.

The broken lines showing a shoe a handle, hardware, and shoulder strap illustrate the portions of the design that form no part of the claim.

1 Claim, 6 Drawing Sheets
